UNITED STATES PATENT OFFICE

2,364,912

FILING CABINET FOLLOWER

John Warren Paxton and George Noble Paxton,
Bloomington, and Irving Richard Cornish,
Elmhurst, Ill.

Original application April 24, 1943, Serial No.
484,392. Divided and this application January
17, 1944, Serial No. 518,566

3 Claims. (Cl. 129—30)

This invention relates to filing cabinets and more particularly to the follower used in the containers therefor whereby the contents are properly supported in vertical position.

The main objects of this invention are to provide an improved form of follower suitable for use in any type of filing cabinet but particularly in a type commonly known as "side-filing;" to provide an improved follower construction which is easily placed in or removed from the container, which rigidly positions itself at any point in the container, but which permits convenient and ready shifting thereof as occasion may require; and to provide an improved follower of this kind which is simple and economical to manufacture, particularly from wood.

In the particular embodiment of the invention herein shown, Fig. 1 is a perspective view of a two-drawer filing cabinet of a construction such as that shown in our co-pending application Serial No. 484,392, filed April 24, 1943, and of which this is a divisional application. The lower container is shown in its open position, and has mounted therein a follower constructed in accordance with the present invention;

Fig. 2 is an enlarged cross-sectional view of the open container showing the improved follower in elevation;

Fig. 3 is a horizontal cross-sectional view taken on the line 3—3 of Fig. 2; and

Fig. 4 is a vertical cross-sectional view of the follower taken on the line 4—4 of Fig. 2.

A filing cabinet constructed in accordance with the disclosure of the aforesaid application comprises a casing 5 in which are tiltably mounted one or more containers 6 for use with which the improved follower 7 is particularly designed.

The container 6 is formed of a front-bottom part 8, a bottom-back part 9, and end members 10 and 11. The bottom-back member 9 is herein shown to be formed of two pieces providing a lateral slot 12 along the middle portion and extending throughout the length thereof.

Suitable pivot mechanism, not shown herein, connects the container 6 to the casing 5 so that it may be swung or tilted back or forth between the closed and open positions illustrated in Fig. 1 of the drawing.

The improved form of follower 7 is made up of two plates or members 13 and 14 slidably mounted one upon the other. The plate 13 has an extension 15 protruding rearwardly through the slot 12 in the bottom-back part 9 of the container 6. To this extension is attached a T-shaped block 16 which engages the back face

of the bottom-back part 9 and in cooperation with the plate 14, as will be more clearly hereinafter pointed out, grips the bottom-back part 9 for positioning the follower 7 in any desired place in the container 6.

The plate 13 is also provided with an extension 17 along its outer edge disposed in the plane of the plate 14. The abutting edges of the plate or member 14 and the extension 17 provide shoulders 18 and 19 biased to the dimensions of the plates. Also, the plate or member 14 has recesses 20 biased at the same angle as the shoulders 18 and 19. Headed pins 21 secured to the plate or member 13 extend through the recesses 20 and retain the plates in their shiftable relationship. Springs 22 interposed between the pins 21 and the bottom of the recesses 20 normally tend to force the plate 14 downwardly with regard to the plate 13. The inclined abutting shoulders 18 and 19 consequently force the inner edge of the plate 14 against the bottom-back part 9 whereby the follower 7 is firmly held in position in the container 6.

Elongated hand holes or openings 23 and 24 are formed near the upper outer corners of the plates or members 13 and 14, respectively. The hand hole or opening 23 is about twice as large as the hand hole or opening 24. Normally the springs 22 shift the plates so that the bottoms of the openings 23 and 24 are in registration with each other. Thus, when the hand is inserted through the registering portions of the openings 23 and 24, the plate 14 may be pulled up against the action of the springs 22 and thereby release the pressure of the block 16 and plate 14 on opposite sides of the bottom-back part 9. This permits the follower 7 to be shifted along the container so long as the hand retains the plate or member 14 in this retracted position with respect to the plate or member 13. Upon withdrawing the hand and releasing the plate or member 14, the springs 22 again shift the member 14 relative to the member 13 whereby the biasedly arranged shoulders 18 and 19 again force the block 16 and plate 14 to grip opposite faces of the bottom-back part 9.

Variations and modifications in the details of the structure and arrangement of the parts may be resorted to within the spirit and coverage of the appended claims.

We claim:

1. In combination with a container for filing cabinets having a wall member formed of a pair of parts spaced to provide a lateral slot throughout the length of said member, a follower com-

prising a pair of relatively shiftable plates having biasedly-arranged coacting shoulders thereon whereby one of said plates is urged to engage the inner face of said wall member, an extension on the other of said plates received in said slot and engageable with the back face of said wall member, and releasable resilient means shifting said plates for causing said one plate and said extension to grip said wall member for positioning said follower in said container.

2. In combination with a container for filing cabinets having a wall member formed of a pair of parts spaced to provide a lateral slot throughout the length of said wall member, a follower comprising a pair of relatively shiftable plates having biasedly-arranged coacting shoulders thereon whereby one of said plates is urged to engage the inner face of said wall member, a T-shaped extension on the other of said plates received in said slot and engageable with the back face of said wall member, slots formed in said one plate and having the same biased disposition as said shoulders, headed pins on said other plate extending through said slots for holding said plates in their assembled relatively shiftable relationship, and springs interposed in said slots between said pins and the bottom of said slots and adapted to shift said plates for causing the grip of said extension and said one plate on said wall member for positioning said follower in said container.

3. In combination with a container for filing cabinets having a wall member formed of a pair of parts spaced to provide a lateral slot throughout the length of said wall member, a follower comprising a pair of relatively shiftable plates having coacting biasedly-arranged shoulders thereon whereby one of said plates is urged to engage the inner face of said wall member, a T-shaped extension on the other of said plates received in said slot and engageable with the back face of said wall member, slots formed in said one plate and having the same biased disposition as said shoulders, headed pins on said other plate extending through said slots for holding said plates in their assembled relatively shiftable relationship, springs interposed in said slots between said pins and the bottom of said slots and adapted to shift said plates for causing the grip of said extension and said one plate on said wall member for positioning said follower in said container, and partially registering hand slots formed in said plates and adapted to permit the retraction of said plates against the action of said springs for releasing the grip of said follower parts on said wall member.
